UNITED STATES PATENT OFFICE.

ROLAND E. HILL, OF DECATUR, ILLINOIS, ASSIGNOR TO WILLIAMS SEALING CORPORATION, OF DECATUR, ILLINOIS, A CORPORATION OF ILLINOIS.

SAFETY DEVICE FOR PRESSES.

Application filed December 11, 1924. Serial No. 755,207.

This invention is a safety device for presses to prevent injury to the hands of the operator. It frequently happens that the operator is not swift enough in withdrawing his fingers from beneath the press head and in that event the press head in descending will injure the fingers.

The object of my invention therefore is to instantly arrest the plunger and press head the moment the press head comes in contact with the fingers of the operator. This I accomplish by connecting the press head to the end of the plunger in such a manner that said press head shall have a limited amount of vertical movement with reference to the end of the plunger and then connecting with the plunger a pawl which is actuated by the vertical movement of the press head and in combination with this pawl carried by the plunger I provide a ratchet upon the guiding standard through which the plunger works which ratchet is so positioned that during the normal operation of the plunger and press head it will travel entirely past the teeth of the ratchet and when the press head comes in contact with the work in the die the movement of the pawl due to the movement of the plunger will have no effect whereas if the movement of the press head begins before the pawl has travelled past the ratchet, as would be the case if the fingers of the operator were in the way, then the pawl will engage the ratchet and immediately arrest the downward movement of the plunger and press head.

The invention consists also in certain details of construction and novelties of combination, all of which will be more fully described hereinafter and set forth in the appended claims.

In the drawings forming a part of this specification, Fig. 1 is a side view of a press to which my invention is applied, the mechanism for actuating the plunger being omitted; Fig. 2 is a face view of that portion of the device to which my invention is applied; Fig. 3 is an enlarged detail sectional view taken through the plunger and press head, certain parts being shown in elevation; Fig. 4 is a horizontal sectional view on the line 4—4 of Fig. 3; and Fig. 5 is a sectional view on the line 5—5 of Fig. 3.

In carrying out my invention I employ a guiding standard 10 in which works the

plunger 11 carrying the press head 12 at the lower end thereof, this press head having an upwardly extending portion 12^a which extends up into the recess 11^a produced in the lower end of the plunger. The press head 60 has a limited amount of vertical movement with reference to the plunger, this being accomplished by cutting a recess 12^b in the upwardly extending portion 12^a and in which works the set screw 11^b screwed through the 65 face of the plunger and resting within the recess 12^b, this set screw limiting the downward movement of the press head and also the upward movement thereof. To prevent turning of the press head I preferably arrange 70 a collar 13 thereon from which project pins 13^a preferably six in number, which pins work in the apertures 14^a produced in the collar 14 rigidly secured upon the exterior of the lower end of the plunger. 75 It will be understood therefore that the press head 12^a is held against rotation with reference to the plunger but has a vertical movement limited by the size of the recess or notch 12^b and the position of the set screw 80 11^b. The upper end of the portion 12^a has a stem 15 adjustably threaded therein, the upper end of this threaded stem being reduced as shown.

Supported by the stem 15 is a tripping 85 stud 16 and a coiled spring 17 is interposed between the lower end of the tripping stud 16 and the adjustable stem 15, the reduced upwardly projecting end of the stem serving to position this coil spring. The stud 16 and coil spring 17 are located in the vertical bore 11^c extending upwardly from and communicating with the chamber 11^a in the lower end of the plunger, this bore 11^c being of such dimensions as to permit the vertical 95 movement of the tripping stud and coil spring and stem. Projecting horizontally outwardly from the tripping stud 16 is a finger 18 working in a horizontal opening 11^d produced in the front side of the plunger and communicating with the bore 11^c. This horizontally projecting finger 18 is adapted to engage an inwardly extending horizontal finger 19 which is connected at its outer end to the shaft 20 journaled in a suitable bearing 21 secured to the face of the plunger and to the end of this shaft 21 is attached the pawl 22 which is adapted to be brought into engagement with the teeth of the ratchet 23 105 which is fastened to the front face of the 110

standard in alignment with pawl 22 and near the lower end of said standard. This pawl 23 is of such length and is so positioned with reference to the pawl 22 that during the normal operation of the plunger and press head, that is, when the press head is not moved upwardly until it comes in contact with the work in the die, the pawl will travel entirely beyond the ratchet. When, however, the press head is caused to move upwardly before its proper time, as for instance by running in contact with the finger of the operator then this upward movement of the press head will cause the tripping stud 16 to move upwardly carrying with it the finger 18 which in turn operates the finger 19, rocks the shaft 20 and throws the pawl 22 into engagement with the ratchet 23 and immediately checks the downward movement of the plunger thereby preventing the crushing of the fingers of the operator. By having the fingers 18 and 19 of considerable length and positioning the pawl so that during the normal operation of the press it will just barely escape the ratchet, it is obvious that a very slight movement of the press head will be sufficient to instantly throw the pawl into engagement with the ratchet and stop the device.

Having thus described my invention, what I claim is:—

1. The combination with a standard, of a plunger movable in the standard and carrying a press head at its lower end, said press head having a limited amount of vertical movement with reference to the plunger, a ratchet arranged upon the face of the standard, a pawl pivotally carried by said plunger and means interposed between the press head and pawl for actuating said pawl when the press head is moved toward the end of the plunger.
2. The combination with a standard, of a plunger sliding therein and carrying a press head at its lower end said press head having a limited vertical movement with ref-

erence to the end of the plunger, a ratchet arranged upon the face of the standard near its lower end, a pawl carried by the plunger and normally moving past the ratchet, an actuating member connected to said pawl and extending into the standard and means connected with said press head for engaging said actuating member, to rock said pawl to engage the ratchet.

3. The combination with a plunger having a press head at the end thereof, of a pawl carried by said plunger, a standard having a ratchet on the face thereof, adjacent the pawl, a finger carried by the pawl, and an actuating finger engaging the pawl finger, said actuating finger being operatively connected with the press head, said press head having a limited amount of vertical movement relative to the plunger.

4. The combination with a standard provided with a ratchet, of a plunger provided with a press head, of means for holding said head against rotation, means for limiting the vertical movement of the press head relative to the plunger, a tripping stud connected with the press head, an actuating finger carried by said stud, a pawl pivoted to the face of the plunger and having a finger engaging the actuating finger whereby upon movement of the press head the pawl will be thrown toward the ratchet.

5. The combination with a standard having a ratchet, of a plunger working in said standard and carrying a pawl upon its outer face, and a vertically movable press head at its lower end, means for connecting said press head to the plunger and holding the same against rotation but permitting vertical movement, a tripping stud having an actuating finger, a finger carried by the pawl and engaging said actuating finger, and yieldable connecting means between the tripping stud and press head.

In testimony whereof, I hereunto affix my signature.

ROLAND E. HILL.
